PERMANENT WAVING APPARATUS

Hobart N. Durham, Munsey Park, N. Y., assignor
to Eugene, Ltd., New York, N. Y., a corporation
of New York

Application April 3, 1935, Serial No. 14,407
In Great Britain December 31, 1934

4 Claims. (Cl. 219—24)

The invention relates to new and useful improvements in permanent waving and to novel and useful methods and devices for permanently waving hair.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, constructions, arrangements, combinations and improvements herein shown and described.

15 The accompanying drawing, referred to herein and constituting a part hereof, illustrates one embodiment of the invention, and together with the description, serves to explain the principles of the invention.

20 Of the drawing:

Fig. 1 is a diagrammatic view of apparatus embodying the invention; and

Fig. 2 is a section showing the devices of Fig. 1 in operation.

25 The invention provides a new method of permanent waving wherein the heat and vapor are created by resistance to electrolytic conduction, and provides also novel apparatus and devices for carrying out said methods. In certain of its 30 features and applications the invention is especially adapted for electrolytically doing croquignole waving in an easy, simple and efficient manner, with a minimum of mechanism, and that of a very simple character. One of the 35 chief objects of the invention is to steam curls electrolytically while eliminating possibility of short circuiting of metal parts and also preventing contact of the hair with any metal or corrodable material, whether in the electrolytic circuit 40 or not. Other objects of the invention are to provide electrolytically operated means for steaming croquignole curls from the inside outwardly and to effect the longest and most intense steaming action at the center of the wound tress.

45 In carrying out my invention, broadly considered, a mandrel upon which the tresses are to be wound is provided, the mandrel being of absorptive material, or otherwise capacitated to carry an electrolyte, the better practice being to 50 pregnate the mandrel with the electrolyte for each successive tress, the electrolyte preferably containing alkaline hair softening ingredients, such as decomposable ammonium salts.

By making the mandrel of rigid absorvent material, such as unglazed porcelain, it can act

as an absorbent electrolyte carrier and effective curl support as well. Thus a curl wound upon the absorbent surface can be heated and steamed without bringing any hair into contact with metal electrodes or other metal parts which sometimes 5 corrode and attack or discolor the hair. Accordingly the invention is especially valuable for use with white or very blond or bleached hair. Also the hair is in direct contact with the energized electrolyte at the surface of the mandrel, thereby being in contact with the heat-creating element of the system but the hair itself is not in the direct path of the electrolytic current, and consequently is not subjected to the sometimes 10 detrimental effects of passing current directly 15 through electrolyte in or on the hair. Furthermore, as the mandrel is a conductor only when moistened with the electrolyte, a metallic short circuit through the mandrel is impossible and thus it is much safer for electrolytic heating than 20 the usual metal mandrels or curling rods which are capable of forming a metallic short circuit in direct contact with the hair and thus dry-heating and sometimes even burning the tress.

25 For croquignole waving the mandrel is preferably of least cross section near its middle and increases in cross section towards its ends, being thus best adapted for croquignole winding, and electrolytically the mandrel during the process has greatest current density and offers greatest 30 electrical resistance at its middle part, within the heaviest part of the tress, thereby getting the earliest, and strongest steaming or heating action within and acting upon the heaviest part of the tress. The mandrel is provided at either end 35 with terminals adapted to be readily connected with and disconnected from circuit terminals, which terminals are in circuit with the low voltage side of a transformer. The current is passed axially of the mandrel and moisture from the 40 enlarged mandrel ends feeds by capillarity to the reduced central portion thereby maintaining the electrolytic circuit. If, as is usual in croquignole waving, the tress is moistened with lotion this lotion also serves to maintain the mandrel moist 45 and conductive.

It will be understood that the foregoing general description of the steps and mechanism of my invention, and the following detailed description as well, are illustrative and exemplary, but 50 are not restrictive of the invention.

Referring now in detail to the illustrated and present preferred embodiment, a mandrel 1 is provided consisting of a rigid, absorptive material, such as a baked clay or unglazed porcelain, 55

or asbestos, cork or other like materials. The mandrel preferably is of least cross section near its middle portion, increasing in cross section toward either end. This presents the most efficient form for croquignole winding and for the electrolytic method of the present invention it also creates a region of greatest current density and electrical resistance at the middle part of the mandrel, and just within the heaviest part 10 of the wound tress. At either end, the mandrel is provided with electrical terminals or electrodes of ample contacting areas, shown as cylindrical conducting members 2 and 3, having openings at 5 and 6 in their inner heads whereby they may 15 be cast or moulded integral with the mandrel itself. Alternatively, the members 2 and 3 may be slidably or screw-connected to the ends of the mandrel to permit ready removal and replacement of electrodes. On their outer heads the 20 terminals are provided with outwardly projecting contact pins 7 and 8, which are split so as to have a spring action. A winding ratchet 9 of usual form is shown near one end of the mandrel 1, preferably being moulded into the ceramic material. The cooperating terminal devices, which are in the secondary circuit of the transformer, comprise knobs or hand pieces 14 and 15 outwardly of insulating material, but having centrally recessed members 16 of conducting 25 material adapted to snap onto and off of the pins 7 and 8. These terminal devices are in the secondary circuit 17 of the transformer 18.

The resistance to electrolytic conduction afforded by the lotion-moistened mandrel serves to 30 vaporize the lotion, heating the wound tress by conduction as well as by the condensation of the lotion vapors.

Various types of clamps may be used, so far as the present invention is concerned and a clamp 40 is conventionally shown at 21 with the mandrel and wound tress mounted thereon. The tress may be covered preparatory to and during the steaming by any suitable cover 22, usually of vapor and moisture impervious material, preferably held in place by any suitable clamping means, such as the spring clip 23.

Due to the relatively long current path afforded by the mandrel, voltages as high as 10 to 50 20 volts may be employed, which are perfectly harmless to the human body and at the same time eliminate the uncertainty of contact which might be encountered at lower voltages in case of any corrosion of the terminals.

The invention in its broader aspects is not 55 limited to the specific mechanisms shown and described but departures may be made therefrom within the scope of the accompanying claims without departing from the principles of the invention and without sacrificing its chief advantages.

What I claim is:

1. As an article of commerce for use in permanent waving, a mandrel of absorptive mate-

rial capacitated to absorb an electrolyte whereby the mandrel will be conductive in an electrolytic circuit when wet with electrolyte and non-conductive when dry, the mandrel being adapted to support a wound tress of hair upon its absorptive surface, and electrodes of opposite polarities spaced from each other and contacting portions of the surface of said mandrel remote from that portion of said surface upon which the hair is wound, whereby the hair is heated by direct contact with the electrolyte-carrying element in the electrolytic heating circuit but does not contact any electrode material in said circuit. 5

2. As an article of commerce for use in permanent waving, a rigid mandrel of absorptive 15 material capacitated to absorb an electrolyte whereby the mandrel will be conductive in an electrolytic circuit when wet with electrolyte and non-conductive when dry, the mandrel being adapted to support a wound tress of hair upon 20 its absorptive surface, and electrodes of opposite polarities spaced from each other and contacting portions of the surface of said mandrel remote from that portion of said surface upon which the hair is wound, whereby the hair is heated by 25 direct contact with the electrolyte-carrying element in the electrolytic heating circuit but does not contact any electrode material in said circuit. 20

3. As an article of commerce for use in permanent waving, a rigid mandrel of absorptive 30 ceramic material capacitated to absorb an electrolyte whereby the mandrel will be conductive in an electrolytic circuit when wet with electrolyte and non-conductive when dry, the mandrel being adapted to support a wound tress of 35 hair upon its absorptive surface, and electrodes of opposite polarities spaced from each other and contacting portions of the surface of said mandrel remote from that portion of said surface upon which the hair is wound, whereby the hair is heated by 40 direct contact with an element in the electrolytic heating circuit but does not contact any electrode material in said circuit. 40

4. As an article of commerce for use in permanent waving, a mandrel of absorptive material 45 capacitated to absorb an electrolyte whereby the mandrel will be conductive in an electrolytic circuit when wet with electrolyte and non-conductive when dry, the mandrel being adapted to support a wound tress of hair upon its absorptive 50 surface, and electrodes of opposite polarities spaced from each other and contacting portions of the surface of said mandrel remote from that portion of said surface upon which the hair is wound, whereby the hair is heated by direct contact with the electrolyte-carrying element in the electrolytic heating circuit but does not contact any electrode material in said circuit, said mandrel having a central portion of reduced cross section to increase the current density and to 55 intensify the heating locally. 60
